UNIVERSAL SHOE FIXTURE FOR
ORTHOPEDIC ATTACHMENTS

Nathan Rosenthal, Newton, Mass.

Application March 20, 1945, Serial No. 583,808

3 Claims. (Cl. 36—8.5)

My present invention is a novel and improved fixture to be secured to boots or shoes adapted to receive and engage detachable rods, braces, or the like extending from the shoe upwardly to support braces for use by the wearer.

Such orthopedic attachments or braces are necessarily arranged for a limited extent of pivotal or other movement to permit the action of the foot relatively with the brace, and are of special importance in cases of partial paralysis, injury to the knee or leg, infantile paralysis cases, or the like.

Heretofore it has been customary to make a special socket-like member for attachment to a particular shoe, such device being especially made to fit the shoe to which it was to be fixed and to support the rods or braces in a pivotal manner. Owing to the difference and difficulties in first fitting shoes to the wearer and then fitting such braces to the patient, it has heretofore been customary to have each socket member individually hammered out, made, fitted, and adjusted by hand to the particular shoe to which it has to be attached, and at the location deemed most advisable.

Such prior fixtures, therefore, have usually comprised a tubular member to which were welded plates and frequently an entire heel plate extending from heel to shank of the shoe were thus built with the tubular socket member, involving an undue amount of weight and rendering such fixture extremely objectionable when a heel was to be attached over the same.

My present invention is directed to provide a type of fixture which can be universally adjusted to any width, size, or position of a shoe, readily equipping a shoe to receive the brace rods.

My improved fixture is extremely light and strong and is so constructed and arranged as to be capable of quick and ready attachment to a shoe, and with relatively no interference with the subsequently heel-attaching operation.

Thus my improved type of fixture enables an article of this description to be readily carried in stock and instantly made adjustable for the width of any shoe to which it is desired to attach the same. Furthermore, by making the tubular or pivot-receiving portion integral with the flange-attaching portion, an extremely rigid and light-weight structure is produced, of a minimum thickness, together with ample strength and with but slight interference for the subsequent attaching of the heel, which usually over-

laps and partly covers either the flange or the tubular fixture portion.

Referring to the drawing illustrating a preferred embodiment:

Fig. 1 is a side elevational view showing my improved universal type of fixture;

Fig. 2 is an end view;

Fig. 3 is a view of one-half the tubular member with the attaching flange shown in uppermost position;

Fig. 4 is illustrative of the fixture separated in the middle and adjusted widthwise to a shoe, and

Fig. 5 is a view showing the tubular member and attaching flange with the wings at each end normally employed to limit the oscillation of the attaching rods removed when desired for freer articulation.

As shown in Fig. 1, my improved device comprises a tubular member 1, formed of thin light steel, aluminum, or the like, to which is secured a pair of horizontal attaching flanges 2 and 3 adjacent the end portions of the tubular member 1, which flanges are perforated at 5—5 to receive rivets to secure the brace to the bottom of the shoe, rivets being usually employed for this purpose and going thru the sole and insole of the shoe to which the fixture is attached. Also, I preferably secure to each end portion of the tubular member 1 a plate 10 having upstanding wings 11 and 12.

These wings are extended outwardly beyond the end portion of the tubular member 1 and upwardly somewhat to constitute a stop or limit for the pivotal action of the brace rods 15, which rods each have a right-angled portion 16 extending into an adjacent part of the tube 1 and with the main portion extending upwardly to the leg brace. Thus, a limited articulation is permitted between the rods 15 and the shoe sole 20 to which the fixture and brace are attached, as shown in dotted lines in Fig. 2.

With my fixture constructed as thus described, it can be readily fitted to the sole of a shoe by removing the heel and applying the plates 2 and 3 in contact with the outer sole 20 of the shoe, securing same rigidly in position by rivets 21 thru the holes 5 in the brace and thru the sole structure of the shoe.

Usually a slight recess of the edge portion of the shoe sole will permit a limited adjustment or range of fitting between the entire fixture and the shoe. But if the sole is wider than the length of the tube 1 between the plates 10—10, then the tubular member can be readily severed on the line

25 of Fig. 1, the tubular member having a peripheral or weakened groove as indicated at 27 for this purpose, as shown in Fig. 4, and each tubular section 22 and 23 individually secured by its own flange and rivets. This permits quick and instant adjustment without the necessity of special manufacture of a fixture for individual shoes of greater width than that for which the fixture was originally designed.

Also, it is frequently desired to have a fixture without the limiting wings 11 and 12, and for this purpose my fixture can be readily sawed thru as indicated at 26, Fig. 1, thus resulting in the form as shown in Fig. 5.

While the attaching flanges 2 and 3 are usually of ample strength to hold the fixture and braces in position, it may be desired to add a further plate 30 underneath the flanges 2 and 3, which plate may be separately riveted to the sole structure 20 by a series of rivets 31-31, and said plate being also perforated to receive the rivets 21 thru the attaching flanges secured to the tubular member. Such a plate may have openings 33 around the heel portion to receive heel nails or rivets, as well as an open part 35 to facilitate the attachment of the heel to the shoe on top of the plate and flange members. As the attaching flanges 2 and 3 are of relatively thin steel or aluminum, they present but slight difficulty to heel-attaching, and the tubular member 1 being also relatively thin, requires but slight cutting away of the heel at the heel brace for fitting the heel onto the shoe after the fixture has been riveted.

My present invention is of special value and importance at the present moment when many war veterans and injured are being rehabilitated by foot and leg braces, and wherein the prior practice of hammering out rough fixtures for each shoe by blacksmith methods involves difficulty, considerable time, and adds unnecessarily to the weight of the patient's shoe.

By means of my present invention, shoe repair establishments anywhere throughout the country can be fitted with my universal shoe fixture and the same can be instantly prepared, fitted, applied, and secured to the wearer's shoe. By sawing thru the tubular member as shown at 25, a ready adjustment for width can be secured

where this is necessary, and two sections can be sawed out, if necessary, to shorten the length of the tubular member, for example in children's footwear.

Also, the wings 11 can be similarly removed and a still further adjustment in special cases can be readily made where it is desired to limit the swinging movement of the press rods 15, for example, in a forward or rearward direction only. Thus, as shown in Fig. 2 at 40, the upper part of the wings 11 or 12 can be readily severed, thus giving an unlimited swinging movement to the brace 15 in that direction, while limiting it in a reverse direction.

This added capability is of importance in special instances and still further renders my improved leg brace of universal adjustable use.

I claim:

1. A universal fixture of the kind described for attachment to the sole structure of boots and shoes, which comprises an integral tubular member with right-angled attaching flanges, said member being adapted for severing in the middle portion to permit widthwise adjustment of the fixture to the shoe.

2. A universal fixture of the kind described for attachment to the sole structure of boots and shoes, which comprises an integral tubular member with right-angled attaching flanges adjacent each end portion of the tube, whereby the tube may be severed in the middle portion, and each end portion individually secured to the shoe, irrespective of the width of the shoe.

3. An improved fixture of the kind described, adapted for pivotal attachment of brace-rods thereto, said fixture comprising a tubular member, a plurality of flanges integral therewith extending at right angles to the length of the tubular member, each flange being intermediate the middle of the tube and an end, each end of the tube being formed with a vertically extending plate carrying a pair of wings adapted to be spaced from and limiting the oscillating movement of an attached brace rod, said fixture being constructed and arranged for severing lengthwise to give adjustment for width on a shoe and for removal of the end plate and wings.

NATHAN ROSENTHAL.
